UNITED STATES PATENT OFFICE.

ABRAHAM HOLTZ, OF BRONX, NEW YORK, ASSIGNOR TO SADINOFF & WENDROFF INC., OF NEW YORK, N. Y., A CORPORATION OF NEW YORK.

TRIMMING AND METHOD OF MAKING SAME.

Application filed September 3, 1927. Serial No. 217,339.

This invention relates to improvements in trimmings for curtains and the like and to a method of making the same.

It has heretofore been known to knit trimmings of open-work formation and to embody therein a decorative fringe. Previously, this has only been done by attaching a plurality of threads constituting the fringe to one edge of the body of the trimming and, in order to obtain certain design effects of the fringe, such as the scalloped effect illustrated in connection with the present invention, it has been necessary to knit the edge to which the fringe is secured of a shape or configuration which will conform to the outline of the attached edge of the fringe.

The present invention aims to overcome certain difficulties encountered in producing an edge on the body of the trimming to conform to the desired contour of the attached edge of a fringe secured to said body. To this end, both edges of the body of the trimming are made straight by a simple knitting process and the threads constituting the fringe are attached to different chain or warp threads of the body extending from one edge thereof toward the other. The fringe threads thus attached to the various chain threads will loosely depend therefrom and cover those portions of the latter threads which lie directly beneath the fringe threads with the result that an ornamental fringe is provided which covers varying portions of the base fabric with other portions thereof forming part of the face of the trimming.

A preferred embodiment of the inventive idea involved is illustrated in the accompanying drawing, wherein:

40 Fig. 1 is a fragmentary plan view of a trimming, partly broken away, showing one application of the present method, and

45 Fig. 2 is an enlarged fragmentary view illustrating the manner of attachment of a group of fringe threads to one of the chain threads of the body.

The present invention is especially useful in the manufacture of trimmings for curtains, but it will of course be understood that the method employed and the resultant product may be used for other purposes with equal facility without departing from the spirit or scope of the invention.

In carrying out the method, the open-work body or foundation fabric, generally

indicated by the numeral 3 is knitted to form a plurality of rows of chain or warp threads 4 which may or may not be connected by the filet 5, it being understood that any desired design of the body of the trimming 60 may be executed provided the same number of rows of chain threads are included in the body throughout its length, or, in other words, as long as the two longitudinal edges of the body are parallel.

65 As the knitting of the body progresses, the fringe 6 is attached to the chain threads 4. The usual effect to be produced with a trimming of the character shown herein is in the nature of a scalloped design, either angular or round, but it is not to be understood that the invention is to be in any wise construed as being limited to such design. In the present instance, the attached edge of the fringe is shown in angularly scalloped 75 form and in the production of said fringe a plurality of groups of threads 7 are employed which while being connected to the chain threads 4 are in looped form as indicated in dotted lines at the lower end of 80 Fig. 1 and in full lines at the upper end of Fig. 2. Each group may consist of a number of threads of different characteristics, such as threads of different sizes, as shown in Fig. 2, and threads of different 85 kinds of material such as silk, cotton, etc., or the fringe may consist of a plurality of single threads, as desired.

86 In each row of warp chains, preferably knitted as indicated in Fig. 2, a group of 90 the fringe threads 7 are looped, while the base fabric is in the act of fabrication, through adjacent chains and permitted to hang and depend from the latter. To produce the scalloped effect, any one of the intermediate rows of warp or chain threads is selected and the first group of fringe threads, to the left of Fig. 1, is attached thereto. The succeeding group is then connected to the next lower adjacent chain 100 thread at a point slightly offset from the point of attachment of the first group. This operation is continued until the lowermost chain thread forming one of the straight edges of the body 3 is reached. To this latter chain thread one or more of the groups 7 may be attached, as shown, and then the operation is continued in a reverse direction until the first mentioned chain thread is 105 reached, whereupon the foregoing operations 110

are repeated. The various groups of fringe threads now lay loosely over the portions of the chain threads which lie below the point of attachment of each group of the former threads to the body and said groups are sufficiently close together to combine to constitute a fringe which forms a covering for those portions of the chain threads lying directly below said groups.

10 Finally, the free or lower ends of the loops 7 may be severed as indicated at 8 to complete the fringe.

I claim:

1. The method of making trimmings for curtains and the like which consists in forming a base warp fabric, and, in the act of fabricating said base fabric, attaching to the

warp threads thereof an ornamental fringe which covers portions of the base fabric of varying width, with the remainder of the 20 base fabric exposed.

2. The method of making trimmings for curtains and the like, which consists in knitting a base warp fabric, and, in the act of knitting said fabric, attaching to different warp threads thereof a plurality of other threads constituting an ornamental fringe which covers varying portions of said fabric in the longitudinal progression thereof, with other portions of said fabric 25 forming part of the face of the trimming.

In testimony whereof I have affixed my signature.

ABRAHAM HOLTZ.
